<img alt="Technical drawing of a mechanical device, likely a press or stamping machine, showing various components and assembly details. The drawing includes a main frame with a base, a central vertical column, and a horizontal beam. Various parts are labeled with numbers 1 through 52, representing different mechanical elements like gears, levers, and supports. A vertical dimension line on the left indicates a height of 9, and a horizontal dimension line at the top indicates a width of 11. An inset diagram in the upper right corner provides a detailed view of a specific mechanism involving a lever system and a spring, with labels 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, AERIAL TRAMWAY

Claire C. Beatty and Elmer J. Lloyd, Worcester, Mass., assignors to The American Steel and Wire Company of New Jersey, a corporation of New Jersey

Application May 21, 1934, Serial No. 726,782

1 Claim. (Cl. 214—41)

This invention relates to aerial tramways, and more particularly to those employing a double overhead track together with a reversible tramway cable.

According to current practice, what is known as a "double" reversible tramway comprises a pair of supporting structures, one at either end of the path through which the tramway is intended to be moved. Two overhead tracks are made to extend between the two supports, on each of which a tramway carrier is disposed so that when one is at the loading end, the other one is at the discharging end. These carriages are adapted for attachment to an adjacently disposed tramway cable, and are also adapted for movement on the tracks by moving the cable in either direction. A great deal of trouble has been experienced in efficiently loading the carriers connected to the carriages which ride upon the tracks, due to the fact that considerable spillage will result if the discharge doors of the carriers are not tightly closed. In addition, extreme care must be taken to discontinue the operation of the conveyer of the loading bin prior to the reversing of the tramway cable driving means which returns the carriers to the other station.

It has therefore been the practice to manually operate the various devices at the proper times, which not only necessitates several attendants but occasions a waste of time.

One object of the present invention is the provision of a novel aerial tramway of the double reversible type in which the carriers are loaded, conveyed and returned by mechanisms which function entirely automatically.

A further object is to provide a novel device of the class described embodying resiliently mounted track sections adjacent the loading bin which will be depressed when the carriers are completely filled with material to be conveyed, and will function to automatically discontinue the operation of the loading conveyer and cause the tramway cable driving means to remove the carriage and carrier from the loading station.

Still another object of the invention is the provision of a novel closing device for the door of the tramway carrier, together with novel means, if it fails to operate, to automatically discontinue the operation of the loading conveyer for the time being.

These and further objects will be apparent after referring to the drawings, in which:

Referring more particularly to the drawings, the numeral 2 designates an overhead track which is made to extend between the various stations of the aerial tramway. Adjacent one end of the track 2 a short section of track 3 is pivoted, as at 4, to one of the supporting structures, which is indicated at 5. The pivoted track 3, on its end remote from the support 5, is provided with a short hood, or guide, 6, which is pivoted thereto as at 7, and adapted to make contact with the end of the track 2.

The support 5, for one end of the tramway, is provided with a superstructure 8 which carries a storage bin 9. A foundation 10 is disposed beneath the support 5 and has mounted thereon a driving sheave 12 for imparting movement to the tramway cable 13. A motor 14 and a gear reduction unit 15 are adjacently mounted on the foundation 10 for driving the driven sheave 12. A pair of idler sheaves 16 are mounted on the superstructure 8 for directing the cable 13 along the tramway track 2.

A wheeled carriage 17 is suitably secured to the cable 13 and adapted for movement on the track 2. A carrier 18 is pivotally supported by the carriage 17 for transporting material to the unloading station. The wheeled carriage 17 is also provided with a tripper shoe 19 on its upper portion for engaging the arm 20 of a switch 21, which is secured to the superstructure. Upon the arrival of the carriage 17 on the pivoted track 3, the switch 21 will act to disconnect the cable driving motor 14.

A pair of shafts 22 and 23 are rotatably mounted adjacent the discharge end of the bin 9 and each adapted to carry a roll 24, around and between which an apron type conveyer belt 25 is disposed. The shaft 23 has a pulley 26 secured thereto for receiving movement through a belt 27 from a pulley 28 which is mounted on the driven end of a gear reduction unit 29, the latter being driven by an adjacently disposed motor 30.

A spring 32 is mounted on the end of a portion of the superstructure 8 which extends directly beneath the free end of the pivoted track 3, and is provided with a spring cage 33 together with a compression adjustment 34. A contact plate 35 is secured to the adjacent end of the pivoted track 3 and adapted for contact with the upper portion of the spring cage 33. A push-button switch 36 is mounted on the superstructure 8 beside the spring cage 33 and in alignment with an adjustable plunger 37 which is supported by the free end of the pivoted track 3 and provided with a lock nut 38.

A spillage pan 40 is mounted on one end of a pivoted table 41 which is disposed beneath the pivoted track 3, and is over-balanced by a weight 42 on the other end thereof. A plunger 43 is disposed directly beneath the spillage pan 40 for actuating a switch 44, to which it is attached. This switch, when closed, discontinues the operation of the motor 30 and stops the apron type conveyer belt 25 in the bin 9. The spillage pan 40 is thus capable of being over-balanced by a leakage of material from and around the carrier 18, and will act to eliminate waste.

The carrier 18 is provided with a discharge door 45 to which there is secured a latch bar 46 which cooperates with a pivoted latch 47 on the carrier. The door latch 47 is operated through a suitable linkage 48 and a control lever 49 adjacent the upper portion of the carrier.

In order to make certain that the door 45 of the carrier 18 is completely closed and fastened, a support 52 is disposed adjacent the spillage pan 40 and carries a pair of aligned journals 53 through which a bar 54 is extended. A bumper 55 is connected to the end of the bar 54 which is adjacent the spillage pan 40, and a pair of springs 56 positioned around the bar 54 both between the journals 53 and between the bumper 55 and the journals. As the carriage 17 actuates the limit switch 21 to discontinue the operation of the motor 14 for the driving sheave 12, the carrier 18 will come in contact with the bumper 55 and, through impact, cause the latch bar 46 to seat in the door latch 47.

Referring to Figure 3 of the drawings, a wiring diagram is illustrated for controlling electrical adjuncts for the various devices previously described, although it is to be understood that any other suitable adjuncts and circuits may be used in lieu thereof without departing from the spirit of the invention. A traveling-nut type limit switch 65 is geared to one of the idler sheaves 16, which are rotated by the tramway cable 13, and serves to reduce the speed of the cable driving motor 14 in three steps prior to the arrival of the carriage 17 on the pivoted track 3. The limit switch 65 is entirely conventional in construction and function, and is accordingly not shown in detail.

As the carrier 18 arrives at the loading point (adjacent the bin 9), the tripper shoe 19 on the top thereof engages the switch arm 20 and actuates the limit switch 21 to stop the motor 14 through a magnetic reversing step accelerating speed controlling resistance 66. The motor 14 is provided with a standard type of spring-set solenoid brake (not shown) which functions, when the power to the motor is cut off, to stop the empty carrier 18 exactly in position before the loading chute of the bin 9. The limit switch 21 at the same time closes the circuit, through a time delay relay 67 and a magnetic non-reversing full-voltage starter 68, to the motor 30 for driving the apron type conveyer belt 25.

The starting of the conveyer motor 30 is thus delayed for a predetermined interval, in order to insure the previous stopping of the carrier 18. As the apron type conveyer belt 25 functions to load the carrier, the pivoted track 3 is gradually depressed against the resistance of the spring 32 and permits the plunger 37 to actuate the push-button switch 36, which closes the circuit to a time delay relay 69. The time delay relay 69, thus put in operation, opens the circuit to the conveyer motor 30, thereby stopping the operation of the apron type conveyer belt 25 and, after a predetermined time interval, closes the circuit to the motor 14 for the driving sheave 12, which has been set by the magnetic reversing step accelerating speed controlling resistance 66 to drive the cable 13 in the opposite direction.

The tramway carriage 17 thus leaves the pivoted track 3 and is brought up to speed, through the motor 14, by the controlling action of the traveling-nut type limit switch 65, in the converse manner in which it reduced its speed prior to stopping and loading, as previously described. As the time delay relay 69 starts the motor 14, after the predetermined interval mentioned, it is also effective to set a time delay relay 70 in operation to stop the motor 30 for the apron type conveyer belt 25, after a predetermined interval. In effect, this last interval is a few seconds longer than the actual time required to load the carrier 18, and will thus serve to eliminate waste in the event that the switch 36 adjacent the spring 32 fails in its function of stopping the conveyer.

A suitable time delay relay (not shown) actuates the magnetic reversing step accelerating speed controlling resistance 66 when the circuit to the motor 14 is opened. This insures the running of the motor in the opposite direction when it is again started, thus reversing the direction of travel of the cable 13 and accordingly the carriage 17.

A conventional drum-type transfer switch 71 is centrally interposed in the circuits for the various electrical adjuncts and is provided with a three-button switch 72 for enabling the manual stopping, and forward and reverse rotation, of the motor 14 for the driving sheave 12, and a two-button switch 73 for manually starting and stopping the motor 30 for the apron type conveyer belt 25.

An additional safety feature is provided in the form of an interlocked circuit 74 between the motor 14 for the driving sheave 12 and the motor 30 for driving the apron type conveyer 25. This prevents the movement of the carriage 17 until after the conveyer is completely stopped.

It will be apparent from the foregoing that the spring 32 may be suitably adjusted by means of the adjustment 34, and the plunger 37 may be likewise adjusted to effect the operation of the switch 36 for any desired weight of material in the carrier 18, and that the entire operation of the apparatus, as described, is completely automatic.

The tramway carrier 18, thus loaded, started and brought up to speed, as previously described, is propelled along the track 2 toward the discharging point by the movement of the tramway cable 13, and at the same time the empty carrier on the adjacent track, is propelled toward the loading point where the cycle of slowing down, stopping, loading and starting again is repeated. The two carriages 17 are so attached to the tramway cable 13 that when the empty carrier 18 is stopped at the loading point the loaded carrier is stopped at the discharging point, where a suitably disposed tripper engages the control lever 49 attached to the carrier 18, thus operating the door release mechanism 48, raising the door latch 47 from its seat on the latch bar 46, permitting the door 45 to be opened, and thus releasing the material contained in the carrier 18.

The method of controlling the operation of the two carriers on a double reversible tramway can also be adapted to control the carrier of a tramway of the "single reversible type" by a slight modification in the arrangement of the various electrical control units. A tramway of the single reversible type consists of a single overhead track on which a single tramway carrier is disposed and suitably attached to an adjacent tramway cable 5 which is arranged in exactly the same manner as the cable for the double reversible tramway.

The foregoing method of controlling the carriers of reversible types of tramways may also be used in conjunction with the apparatus of Patent No. 1,652,209, to Morrison, which utilizes the reversing action of the carrier to operate the bucket door latch. This combination enables the carriers to be automatically loaded, sent out and the load dumped at any point along the overhead track by merely changing the location of the carriers with respect to each other along the tramway cable.

While we have shown and described one specific embodiment of our invention, it will be understood that we do not wish to be limited exactly thereto, since various modifications may be made without departing from the scope of our invention, as defined in the following claim.

We claim:

A conveyer comprising two conveyer tracks, a tramway cable adjacent said tracks, a carriage mounted on each of said tracks and secured to said cable, a carrier suspended from each of said carriages, said carriers having discharge doors and fastening means therefor, a bin disposed adjacent said tracks, a discharge chute for said bin, a conveyer in said discharge chute, means for driving said conveyer, means for driving said tramway cable in either direction, means for controlling the movement of said cable, spring-mounted track sections adjacent the discharge chute of said bin, means associated with said spring-mounted track sections for actuating the means for controlling the movement of said cable, means adjacent said track sections for insuring the operation of the fastening means for the discharge door of said carriers, means for discontinuing the operation of said conveyer if said door fastening means fails to operate, said last named means comprising a pivoted platform beneath said spring-mounted track sections, a spillage pan on said platform, and a switch operated by the depression of said platform for disconnecting said conveyer driving means.
